DOOR LOCK

William S. Edwards, Hamden, Conn., assignor to
 Sargent & Company, New Haven, Conn., a corporation of Connecticut

Application July 17, 1939, Serial No. 284,813

10 Claims. (Cl. 70—92)

This invention relates to door locks, and more particularly to a lock adapted to be applied to the door of a public building, and designed for use in connection with a so-called panic bar, which normally lies across the inner face of the door in such a manner that persons crowding against the same will automatically release the latch and allow the door to swing open. It will be understood, however, that while my improvements may 10 be particularly adapted, generally speaking, for a lock of this type, certain features of my invention are applicable to and useful in locks or latches of other types.

In connection with so-called panic bar locks, 15 the bolts are in some instances pivoted adjacent the face plate of the lock so that when released by depression of the panic bar, for example, the bolt will roll or swing inwardly by pressure against the strike plate, and permit the door to 20 open without the bolt being positively retracted by a sliding movement within the lock case. In some instances people did not understand the operation of these locks, and when upon depression of the panic bar a positive retraction of the 25 bolt did not occur, it was sometimes felt that the lock was not in proper working order, notwithstanding the fact that the bolt was released so that it would swing pivotally by contact with the strike plate so as to permit the door to open 30 readily.

The present invention has particularly to do 35 with a lock of the pivoted bolt type, and has for its object the provision of mechanism whereby the bolt is not only released for a pivotal swinging movement when an opening pressure is put upon the door, but the bolt is also by depression of the panic bar positively moved to retracted position so that its operation can be readily seen. It will, of course, be understood that this positive 40 retraction of the bolt by the panic bar is not absolutely essential to the opening of the door, for when the bolt is released it will swing upon its pivot and be retracted by contact with the strike.

Another object of the invention is the provision 45 of improved operating mechanism for a so-called panic bar lock.

Another object of the invention is the provision of improved means whereby actuation of an operating member will both release the bolt for 50 swinging movement upon its pivot and positively retract it by a sliding movement within the lock case.

To these and other ends the invention consists 55 in the novel features and combinations of parts to be hereinafter described and claimed.

In the accompanying drawings:

Fig. 1 is an edge elevational view of a portion of a door provided with my improved lock;

Fig. 2 is a side elevational view of the parts shown in Fig. 1;

Fig. 3 is a view of the lock with the cover of the case removed to show the interior mechanism;

Fig. 4 is a view similar to Fig. 3 with the parts in the position assumed when the door is closed, some of the mechanism having been removed for 10 the sake of clearness;

Fig. 5 is a view similar to Fig. 4 showing the parts in the position assumed when the door is closed and the bolt is retracted;

Fig. 6 is a sectional view on line 6—6 of Fig. 4; 15

Fig. 7 is a view similar to Fig. 6 showing the bolt when moved about its pivotal connection with the case;

Fig. 8 is a detail view of the bolt-operating slide 20 actuated from the interior of the door; and

Fig. 9 is a view of an associated slide designed to be operated from the exterior of the door.

Fig. 10 is a view in elevation of the retracting slide for the dog-controlling plunger and latch bolt.

In order to illustrate a preferred embodiment of my invention I have shown a door 10 equipped with a lock of the type known as a mortise lock and having a case 11 and a face plate 12 designed to lie substantially flush with the edge of the 30 door, which face plate is provided with openings 13 and 14 through which project a dog-controlling plunger 15 and a bolt 16 of the beveled or latch bolt type. Upon the inside of the door I have shown an escutcheon plate 17 to which is 35 pivoted at 18 a panic bar 19, the latter being provided with a finger 20 projecting below the lock case to actuate the bolt-operating slide, as will be hereinafter more fully described.

The bolt 16 is provided with a stem 21, the stem being pivoted to the bolt head at 22, as shown more particularly in Fig. 6. A spring 23 surrounds the stem and acts against posts 24 of the case at its rear end, and against a washer 25 secured on the stem 21 at its front end so as to 40 urge the bolt to protracted position. At its rear end the stem is provided with the usual crosshead 26.

It will be noted from Fig. 6, for example, that upon each side of the bolt are provided projecting 50 trunnions 27 (only one of which is shown in the drawings), these trunnions being slidably mounted upon lugs 28 at each side of the bolt. It will be understood that these trunnions permit the bolt to swing or pivot upon the lugs 28, as 55

shown, for example, in Fig. 7, this pivotal motion being permitted relatively to the stem 21 by means of the pivotal connection between the bolt and stem, as shown at 22.

5 The bolt is controlled by means of a slide, shown more particularly in Figs. 3 and 8, and designated generally by the numeral 30. This slide has a lower portion 31 extending to the bottom of the case, the lower surface 32 of which portion is exposed through an opening 33 at the bottom of the case, so that it may be contacted by the operating finger 20 of the panic bar 19. The slide 30 also is provided with an inwardly projecting part 34, which, as shown in Fig. 4, lies behind the crosshead 26 when the slide is in its lowermost position to dog the stem 21 against retraction and thereby dog the bolt in protracted position.

A latch-retracting lever 35 is pivoted in the case at 36, the upper free end of which lever lies 20 in front of the crosshead 26 so as to retract the stem 21 and bolt 16 in a sliding movement when this lever is actuated. The lever 35 is provided with a projection 37 adapted to be contacted by a lug 38 at the lower end of the slide 30, so that 25 when this slide is raised by the finger 20, for example, the lever 35 will be swung about its pivot in a direction to retract the bolt stem 21. The slide 30 is ordinarily maintained in its lower position by means of a spring 39, shown in Fig. 3. 30 The latch bolt is also adapted to be released and withdrawn by means at the outside of the door, such, for example, as the knob 40. This knob may operate, through means which forms no part of the present invention and which it is therefore 35 not necessary to show, an arm 41 (Figs. 3, 4 and 5), which rests below an auxiliary slide 42 mounted in the case adjacent the slide 30. The slide 42 is held in its lower position by the spring 43, and carries upon its rear face, as shown in 40 Fig. 9, a lug 44 adapted to engage in the recess 45 on the slide 30, so as to raise the latter slide when the auxiliary slide 42 is raised.

The dog-controlling plunger 15 is, as shown in Figs. 4 and 5, provided with a stem 46 slidable 45 between posts 47 fixed in the case, and is provided with a rear crosshead 48. A spring 49 acts in the usual manner to maintain this plunger in its protracted position. When in its protracted position, as shown in Fig. 3, for example, the crosshead 48 engages the rear face of a depending lever 50 pivoted at 51 within the case, so as to urge this lever to the left, as shown in this figure. The lower end of the lever 50 engages the upper end of a bell crank lever 52 pivoted at 53 to the case, 55 the other end of which bell crank lever engages below a projection 54 on the slide 30, whereby when the lever 50 and dog-controlling plunger are in the position shown in Fig. 3, the bell crank lever 52 is rocked slightly about its pivot in a 60 counterclockwise direction, thus raising the slide 30 so that the projection 34 clears the crosshead 26. This is the position occupied by the parts when the door is open, and if it is closed in the usual manner, the beveled bolt 16 is cammed into 65 the case by contact with the strike.

When the door is closed the parts are in the position shown in Fig. 4, from which it will be seen that the dog-controlling plunger 15 has been 70 swung inwardly about its pivot by contact with the strike while the latch bolt 16 is projected into the strike opening. In this position the crosshead 48 is moved away from the lever 50, and thus allows the spring 39 to move the slide 30 downwardly, keeping the upper end of the bell 75 crank lever 52 against the lower end of the lever

50. In this position the projecting portion 34 of the slide 30 stands behind the crosshead 26 of the latch bolt stem 21, so that the latch bolt may not be cammed rearwardly into the case. It will be noticed that the lower end of the slide 30 is in this position of the parts in its lowermost position, resting against the finger 20.

If it is desired to open the door, the panic bar 19 may be depressed, which raises the slide 30 and carries the part 34 upwardly to a position where 10 it no longer blocks the inward movement of the crosshead 26. This raising of the slide 30 at once frees the bolt 16 for swinging movement about the trunnions 27, if an outward pressure is put upon the door, so that the bolt will swing from 15 the position shown in Fig. 6 to that shown in Fig. 7, and then be cammed inwardly, permitting the door to open. Also a continued movement of the panic bar and consequent lifting of the slide 30 operates the latch-retracting lever 35 so as to 20 positively retract the bolt 16 within the case by a sliding movement, and free the bolt from contact with the strike, so that the door is free to open without making use of the pivotal arrangement of this bolt.

The dog-controlling plunger 15 is pivoted adjacent the rear side of the face plate 12 by means of trunnions 55, which trunnions are normally held in recesses 56 provided at the rear of the face plate by the finger 57 on a lever 58 pivoted to 30 the case at 59 and urged in a counter-clockwise direction by the spring 60 (Fig. 3). It is desirable to be able to lock the plunger 15 and the bolt 16 in retracted position at times, so that the door will swing open and shut freely without 35 use of the panic bar 19 or knob 40. This is arranged by means of a slide 65 mounted within the case, the slide carrying a tumbler 66 and having a talon 67 designed to be engaged by the rollback 68, so that the slide may be moved forwardly and rearwardly within the case, and maintained in either its forward or rearward position by the engagement of the tumbler 66 with abutments 69 and 70, shown more especially in 40 Figs. 4 and 5. The slide 65 carries a depending 45 finger 71 which acts against the crosshead 26 to retract the bolt 16, and adjacent its front end is provided with a shoulder 72 which acts against the crosshead 48 to withdraw the plunger 15. Preferably the roll back 68 will be operated by 50 means at the inside of the door such as a lock 74 or a thumb turn if the latter is desired. It may also be noted that the finger 71 in the extreme forward position of the slide 65, stands above the finger 73 on the slide 42 (Fig. 9), so as to dog this 55 slide against upward movement and prevent operation of the knob 40 at the outside of the door. It will also be understood that a key-operated lock 75 may be provided at the outside of the door, which lock will have a rollback standing in a position similar to but spaced slightly in front of the roll back 68, which may be operated to act upon the lug 76 at the upper end of the slide 30 to raise this slide and thereby release or withdraw, or both release and withdraw, the bolt 16.

It will be seen that I have provided a panic bar lock of very simple construction, but having all of the operations and advantages of the usual lock of this character. In addition it will be seen that the bolt 16 is not only pivoted to the 70 case so as to be released immediately upon depression of the panic bar so that it will be permitted to swing upon its pivot by outward pressure upon the door, and permit the door to open, but also provision is made for the positive retrac- 75

tion of this bolt within the lock case by depression of the same panic bar without the use of mechanism of any great complication.

While I have shown and described a preferred embodiment of my invention, it will be understood that it is not to be limited to all of the details shown, but is capable of modification and variation within the spirit of the invention and within the scope of the appended claims.

10. What I claim is:

1. In combination, a lock case, a latch bolt slidably mounted therein, said bolt also having a pivotal connection with the case, a stem connected to the bolt and slidably mounted in the case to control both slidable and pivotal movements of the bolt, a slide movably mounted in the case, said slide having a part normally standing in the path of said stem to dog the bolt against movement, and means actuated by the movement of said slide to slidably retract the bolt into the case after said dog has been moved out of the path of the stem.

2. In combination, a lock case, a latch bolt slidably mounted therein, said bolt also having a pivotal connection with the case, a stem connected to the bolt and slidably mounted in the case to control both slidable and pivotal movements of the bolt, a slide movably mounted in the case and having a part normally dogging the stem against movement, and a latch-retracting lever pivotally mounted in the case and adapted to be moved by said slide to positively retract the latch into the case.

3. In combination, a lock case, a latch bolt slidably mounted therein, said bolt also having a pivotal connection with the case, a stem connected to the bolt and slidably mounted in the case to control both slidable and pivotal movements of the bolt, a slide movably mounted in the case and having a part normally dogging the stem against movement, a latch-retracting lever pivotally mounted in the case and adapted to be moved by said slide to positively retract the latch bolt into the case, and means pivoted to the door on the outside thereof to actuate said slide to release said dogging means and thereafter slidably retract the bolt.

4. In combination, a lock case, a latch bolt slidably mounted in the case and also having a pivotal connection with the case, means to dog said bolt against movement, a bolt-retracting lever movably mounted in the case, a slide upon which said dogging means is mounted, and means connecting said lever and slide whereby the former is actuated by the latter to slidably retract the bolt after release of the bolt from said dogging means.

5. In combination, a lock case, a latch bolt slidably mounted in the case and also having a pivotal connection with the case, means to dog said bolt against movement, a bolt-retracting lever movably mounted in the case, a slide upon which said dogging means is mounted, means connecting said lever and slide whereby the for-

mer is actuated by the latter to slidably retract the bolt after release of the bolt from said dogging means, and key-operated means to actuate said slide.

6. In combination, a lock case, a latch bolt 5 slidably mounted in the case and also having a pivotal connection with the case, a stem connected to the latch bolt and slidably mounted in the case to control both slidable and pivotal movements of the bolt, means to dog said stem 10 against movement, means mounted in the case to release said dogging means to permit movement of the bolt, means movably mounted in the case to engage said stem and slidably retract the bolt, and a single member to operate both said 15 releasing means and said actuating means.

7. In combination, a lock case, a latch bolt slidably mounted therein, said bolt also having a pivotal connection with the case, a stem connected to the bolt and slidably mounted in the 20 case to control both slidable and pivotal movements of the bolt, a member movably mounted in the case having a part normally standing in the path of the stem to dog the bolt against movement, and means actuated by said member to 25 slidably retract the bolt into the case after said dog has been moved out of the path of the stem.

8. In combination, a lock case, a latch bolt slidably mounted therein, said bolt also having a pivotal connection with the case, a stem connected to the bolt and slidably mounted in the 30 case to control both slidable and pivotal movements of the bolt, a member movably mounted in the case to dog said stem in position to prevent retraction of the bolt, means operated by 35 said member to slidably retract the bolt and means to actuate said dogging member.

9. In combination, a lock case, a latch bolt slidably mounted therein, said bolt also having a pivotal connection with the case, a stem connected to the bolt and slidably mounted in the 40 case to control both slidable and pivotal movements of the bolt, a member movably mounted in the case provided with means to dog said stem in position to hold the bolt protracted, a lever 45 mounted in the case and actuated by said member to engage said stem and slidably retract the bolt, means mounting said lever to provide a lost-motion connection between it and said member whereby the dogging member is moved prior 50 to said lever and means to actuate said dogging member.

10. In combination, a lock case, a latch bolt mounted therein for movement to protracted and retracted positions, a stem connected to the bolt 55 and slidably mounted in the case, a dogging member movably mounted in the case and adapted to engage said stem to hold the bolt in protracted position, a latch-retracting lever actuated by the movement of said dogging member to 60 engage the stem and move the bolt to retracted position and means to operate said dogging member.

WILLIAM S. EDWARDS.
